[57] CLAIM

The ornamental design for wall mounted merchandise display stand, as shown and described.

DESCRIPTION

FIG. 1 is a side elevational view of a wall mounted merchandise display stand showing my new design, the opposite side being a mirror image thereof;
FIG. 2 is a top plan view thereof;
FIG. 3 is a rear elevational view thereof;
FIG. 4 is a bottom plan view thereof;
FIG. 5 is a perspective view thereof;
FIG. 6 is an enlarged fragmentary elevational view taken along line 6—6 of FIG. 2; and
FIG. 7 is a sectional view taken along line 7—7 of FIG. 4.
